UNITED STATES PATENT OFFICE.

WILHELM KLÖNNE, OF RATH, NEAR DÜSSELDORF, GERMANY.

COKE-OVEN.

No. 825,221.

Specification of Letters Patent.

Patented July 3, 1906.

Application filed October 26, 1905. Serial No. 284,322.

To all whom it may concern:

Be it known that I, WILHELM KLÖNNE, engineer, a subject of the German Emperor, residing at Rath, near Düsseldorf, Germany, have invented a new and useful Coke-Oven, of which the following is a specification.

My invention relates to such a horizontal coke-oven as is provided with vertical heating-channels, draft-alternator, and regenerator for the combustion-air, in which oven there are arranged two parallel longitudinal channels below each chamber-floor which alternately admit hot air and lead away the heated gaseous products.

This invention consists in the production of independent heating with alternating draft for both halves of the oven by the arrangement of two channels in series below each half of the oven able to be set in operation alternatively, each half of the bottom channel being at the same time in connection with a regenerator. By this arrangement, therefore, each half of the oven can be kept constantly heated and a highly-forced movement of gas and air can be obtained, whereas in ovens with alternating draft of usual construction one half of the oven must always be completely deprived of heat. Thereby variations of the temperature arise which are avoided by the construction of my oven.

The object of my invention is shown on the accompanying drawings, in which—

Figure 1 illustrates a section on line 1 2 of Fig. 3; Fig. 2, a section on line 3 4 5 6 of the same figure, and Fig. 3 a section on line 7 8 of Fig. 1.

The gas serving for heating the walls of the oven is alternately taken from the gas-conducting pipe *a* and the conducting-pipe *b*. When the heating-gas is taken from the first, the gas passes through the nozzle-pipe *c* into the channel *d*. From here it is equally divided by the openings *e* among the individual heating-channels *f* and, rising in these latter, collects in the upper channel *g*. Then the gases fall within the channels *h* and flow through the openings *i* into the floor-channel *k* and arrive through the flue *l* in the regen-

erator *R*. The regenerator *R*, which is fitted with a lattice-like stonework, is heated by the waste gases. The waste gases are cooled within the same and pass into the chimney. The air necessary for combustion is forced into the regenerator *R'*. It becomes heated therein and flows through the flue *l'* into the floor-channel *k'* and is equally divided by the openings *i'* among the heating-channels *f*. The operation continues until the regenerator *R* is heated. Then the gas-conducting pipe *a* is closed and the gases are taken from the pipe *b*. The gases flow through the nozzle-pipes *c'* into the channel *d'* and are equally divided by the openings *e'* among the heating-channels *h* and rise inside the same. They collect in the channel *g* and flow down through the heating-channels *f*, passing through the openings *i'* into the floor-channel *k'*. Then they arrive through flue *l'* in the regenerator *R'*, heat the same, and flow then to the chimney. The air necessary for combustion is this time forced into the regenerator *R*. Within this the air is heated and enters the floor-channel *k* through the flue *l*, being equally divided by the openings *i* among the heating-channels *h*. The heating process for the second half of the oven is the same as described above.

In my construction the conducting-channel *g* can be made lower than hitherto, and thus the binders can be extended upward, whereby a greater stability of the oven-walls is obtained.

What I claim as my invention is—

In a coke-oven the combination of two chambers with vertical heating-channels, a combustion-gas-conducting pipe for each half of each chamber, two floor-channels in series below each chamber able to be set in operation alternatively, and regenerators to be set alternatively in connection with one of these channels, as and for the purpose specified.

WILHELM KLÖNNE.
